SKIVING MACHINE

Eugene J. Ray, Beverly, Mass., assignor to United
Shoe Machinery Corporation, Borough of
Flemington, N. J., a corporation of New Jersey

Application April 19, 1939, Serial No. 268,718

14 Claims. (Cl. 69—9.5)

This invention relates to skiving machines and is herein illustrated as embodied in a machine having a tubular knife, said machine being particularly adapted to skive pieces of sheet material, such as leather, which are to be incorporated in boots and shoes.

Machines of this general type have hitherto had a hollow frame of greater length than width and having substantially upright sides and a flat horizontal top through which a portion of the knife projects. The operator sits facing one of the long sides of the frame and presents the pieces of work over a portion of the flat horizontal top of the frame to the projecting portion of the tubular knife. The horizontal position of the top has necessitated a somewhat tiring posture on the part of the operator. This position has also necessitated a considerable distance from the front wall of the frame to the adjacent edge of the knife where it projects above, so that the operator was unable to grasp small pieces of work and present them to the knife with his fingers close to said edge.

According, therefore, to one feature of the invention, the top of the machine slopes upward from front to rear, the feed roll is yieldable about an axis which is parallel to the top, and the presser is arranged to exert its force in a direction perpendicular to said top. With such a construction the presentation of all kinds of pieces of work is facilitated.

In machines of this general type it is sometimes desired to use a presser in the form of a presser foot or an idle presser roll which requires no driving mechanism, while at other times it is desired to use a driven presser roll; and commonly a machine having a head fitted with a presser foot or an idle presser roll has been used in one case and another machine fitted with a driven presser roll in the other. According to a further feature of the present invention, the hollow frame has an opening in its top over which a head may be detachably fastened, the head which carries a driven presser roll having a portion which extends down through said opening and being provided with mechanism for driving the presser roll from a moving part located inside the frame of the machine. With such a construction it is necessary merely to change heads when it is desired to change from a presser which is driven to one which is not, or vice versa.

These and other features of the invention, including certain details of construction and combinations of parts, will be set forth as embodied

in an illustrated machine and pointed out in the appended claims.

Referring to the accompanying drawings,

Fig. 1 is a front view, principally in elevation, of a machine in which the present invention is embodied, part of the wall of the frame having been broken away to expose certain other parts which are shown in section;

Fig. 1^a is a detail, principally in section, showing more particularly part of the mechanism for rotating the presser roll;

Fig. 2 is a view, partly in plan and partly in section, of the parts of the machine which are located beneath the top of the frame;

Fig. 3 is an end view of the machine, partly in section and partly in elevation;

Fig. 4 is a detail in section showing the feed roll and part of the mechanism for driving it;

Fig. 5 is a view looking down upon a part of the machine from which the head has been removed;

Fig. 6 is a view, partly in section and partly in elevation, of the knife, the feed roll and their mountings;

Fig. 7 is a detail, principally in plan view, of the grinder and a part of the knife;

Fig. 8 is a longitudinal section through the hub of the member which carries the grinder; and

Fig. 9 is a detail in elevation of a part of the mechanism for rotating the shaft from which the feed roll is driven.

Referring first to Figs. 1, 2 and 6, the mounting of the tubular knife 17 will be described. The knife shaft 15 (Fig. 6) has at its inner end a flange, and projecting from the middle of the flange a cylindrical extension which fits into a bore in the center of the rear wall of the knife 17, the knife being fastened to the flange by screws 19 which pass through holes in the rear wall of the knife and are threaded into ears on the flange. The knife shaft is mounted in and adjustable with a horizontally adjustable, cylindrical carrier 21, said knife shaft being rotatably mounted in two ball thrust bearings 23 (Figs. 1 and 6), said bearings being mounted in the cylindrical carrier 21 and spaced apart by a sleeve 25. The bearings are held respectively from movement away from the ends of the sleeve by a shoulder on the forward end of the shaft 15 and by a cap 26 which is threaded on a portion of reduced diameter at the rear end of the shaft. A collar 27 (Fig. 1), which is fastened to the rear end of the cylindrical carrier 21, engages 55 the right-hand face of the outer ring of the rear

ball bearing 23; and a spring-pressed collar 29 (Fig. 6) engages the left-hand face of the outer ring of the forward ball bearing 23, said collar being acted upon by springs carried in sockets formed in a collar 31, which is fastened by screws to the forward end of the cylindrical carrier 21. These ball bearings are of the type known as radial thrust bearings and the details of their construction form no part of the present invention.

The cap 26, which is threaded upon the rear end of the shaft 15, has an enlarged head provided with two diametrically opposite slots to receive driving pins 35 carried by a pulley 37, which is keyed to the forward end of a short driving shaft 39, said shaft being mounted in ball bearings 41 and having keyed to its rear end three pulleys 43, 45, 47, which are integral with one another. A belt 49, driven from any suitable source of power, runs around the pulley 47. The pulleys 43, 45, as will presently be explained, are part of a change speed mechanism for rotating the feed roll of the machine, and the pulley 37 serves, through suitable connections, to rotate the grinder. The cylindrical knife shaft carrier 21 is mounted for longitudinal sliding movement in a split bearing in the frame of the machine and is held in adjusted longitudinal position by a pinch bolt 51 (Fig. 2) having a nut 53 threaded on one end. Rotatably mounted on the pinch bolt is a sleeve 55, having at its outer end a head by which it may readily be turned and having at its inner end a pinion 57 which meshes with a rack 59 formed on the underside of the cylindrical carrier 21. After the pinch bolt has been loosened, the sleeve 55 may be turned to adjust the whole knife assembly, including the cylindrical carrier 21 with its ball bearings, the knife 17 and the knife shaft 15, the slots in the head of the cap 26 permitting such adjustment while maintaining the driving connection between the cap and the pins 35.

The knife (Fig. 6) is provided with a saucer-shaped chip deflector 61 fastened to a flange at the outer end of a hollow stem 63, the inner reduced end of which is threaded into the knife shaft 15. A locking screw 65, threaded into the hollow stem 63 and adapted at its inner end to contact with the bottom of the socket into which the stem 63 is threaded, furnishes means for locking the chip deflector in adjusted longitudinal position. This construction provides for adjustment of the chip deflector longitudinally of the knife to compensate for shortening of the knife due to its being ground.

A grinder 67 (Figs. 3 and 7) of the annular type is so mounted that the plane of its operative face is at an angle of about 15° to the axis of the knife shaft 15, the construction being such that as the knife 17 is ground away the angle of the bevel of the knife is maintained always the same. To this end, the grinder is mounted in a head 69 fast to the inner end of a shaft 71, which is rotatably mounted in ball bearings carried by a casing 73, said shaft having fast to it a spiral gear 75. The casing 73 has integral with and at an angle to it a long hub rotatable about the axis of a shaft 85 which is parallel to the knife shaft 15, said shaft 85 having a spiral gear 87 in mesh with the spiral gear 75 on the grinder shaft. The hub of the casing 73 has fastened to it by set screws 88 two spaced alined sleeves 89, 91, which are rotatable, respectively, in bearings 93, 95 carried by a plate 97, which is fastened by screws 99 to the frame of the ma-

chine. In the space between these two sleeves, the shaft 85 is of reduced diameter and on it is pinned the spiral gear 87. This shaft extends through a bore in the sleeve 91, and its reduced end extends into a bore in the sleeve 89. Near its right-hand end, the sleeve 91 has a downwardly extending, bifurcated arm having alined bores in which is rotatably mounted a pin 101 through which is threaded the end of an adjusting rod 103. This rod (Fig. 2) extends out through the front wall of the frame of the machine and has attached to its outer end a hand wheel 105, by which it may be turned. Inside the wall of the frame, the rod 103 has formed upon it a ball 107 which is held in a hemispherical socket in a boss formed on the wall. The ball is maintained at all times pressed into the hemispherical socket by a tension spring 109 fastened at its upper end to the top wall of the frame and at its lower end to a pin 111 on a generally horizontal arm which projects from the right-hand end of the sleeve 91. With this construction, when the adjusting rod 103 is turned, the grinder is swung into or out of contact with the knife about the axis of the shaft 85, that is, about an axis which is parallel to the axis of rotation of the knife. Since the knife is adjusted for wear by turning the sleeve 55 (Fig. 2), as has been explained above, its edge is maintained in the vertical plane shown, and consequently the angle or bevel of the edge of the knife is always the same. The grinder driving shaft 85 (Fig. 2) extends well to the right-hand end of the machine, passes through a bearing 113 and has fast to it a pulley 115, around which and around the pulley 37 on the knife shaft passes a belt 117. A belt shifter 119 provides means for shifting the belt to a groove 120 in a stationary member when desired, the belt shifting mechanism being preferably of the kind disclosed in United States Letters Patent No. 2,021,964, granted November 26, 1935, upon an application filed in my name.

As is common in skiving machines of this general type, the feed roll is mounted in an auxiliary part 121 of the frame (Fig. 2), which is pivoted about the axis of a vertical pin 123 to the main part 125 of the frame; and the main part is pivoted about a horizontal rod 126 carried by ears formed on the base 128. The auxiliary part is held in the closed position shown by a lock which may be rendered operative or inoperative by turning a handle 127. The feed roll 129 is driven from a short horizontal shaft 131 mounted in bearings in the auxiliary part of the frame and having near its outer end, a ball thrust bearing 133, a cover 134 being provided for the recess in which the bearing is located. The other end of the shaft 131 is enlarged and provided with radial teeth 135 which, when the auxiliary part of the frame is in closed position as shown, engage similar teeth on the adjacent enlarged end of an alined shaft 137 mounted in bearings carried by the main part of the frame. The short shaft 131 carries a worm 139 (see also Fig. 4), which meshes with a worm gear 141 fast to one end of a short shaft 143, said shaft extending through a bearing sleeve carried by the auxiliary part of the frame and having a nut 145 threaded on its outer end. The worm gear 141 is located in the base of a cylindrical socket formed in the auxiliary part of the frame; and in the open end of the socket is fitted a thick washer 147, which is held in place by a set screw (not shown). The inner end of the shaft 143 is of enlarged diameter and is provided with a socket and slots to receive a ball

and a pin at one end of a short link 149, the other end of which is similarly connected to one end of the feed roll 129. These two universal joints permit the feed roll to yield in a manner presently to be described, while maintaining the driving connections between the shaft 143 and the roll.

The main part 125 of the frame is in the general shape of a rectangular box, except that it has no bottom wall and no end wall adjacent to the auxiliary part 124. When the main part of the frame and the auxiliary part are, as shown, in the position which they occupy when the machine is being operated, the tops and sides of the two parts are flush with each other. It will be noted, as best shown in Fig. 5, that the top of the part 124 of the frame includes a throat plate 155, the upper surface of which is flush with the upper surface of the top of said part and forms part of said top. The operator, who is seated in front of the machine, that is, in approximately the position of the observer in Fig. 1, presents the pieces of work from left to right over the top of the auxiliary part of the frame to the feed roll and knife.

Machines of the general type under discussion have been made in two forms: (1) with a frame comprising a main part and a swinging part, as in the illustrated machine; and (2) with a one-piece frame. Inasmuch as both types of frame are substantially alike when the swinging part of type No. 1 is in closed operating position, the word "frame" in the following explanation of one feature of the present machine will be used as inclusive of the whole frame in the position it occupies when the machine is running. Hitherto, in machines of this type, the front wall, the right-hand wall as viewed in Fig. 3, has been substantially vertical except for a rather abrupt curve at its top, and the top of the frame has been horizontal. With such a construction, particularly if a knife of comparatively large diameter is used, a considerable extent of the horizontal surface of the top of the frame separates the top of the front wall from that locality on the tubular knife adjacent to the wall which projects above said surface. That is, there has been a considerable distance between the localities which correspond to the localities *x* and *y* (Fig. 3) of the present machine. The operator, as has been explained, sits at the right of the machine, as viewed in Fig. 3, with his left side toward the observer and presents pieces of work from left to right over the top of the frame to the knife and feed roll. The horizontal position of the top of the frame has necessitated a somewhat tiring posture on the part of the operator, who is obliged to lean over more or less toward the machine as he presents pieces of work to it; and the distance between the top of the front wall and the adjacent portion of the exposed edge of the knife has interfered with the presentation of small pieces of work, since the operator has been unable to grasp such small pieces of work close to the locality on the knife which was to operate upon them. In order to remedy these defects, the greater part of the front wall of the present machine is curved toward the knife, and the top wall, instead of being horizontal, is inclined upwardly away from the front of the machine, that is, away from the operator, the axis of the feed roll when no work is in the machine being inclined in a direction parallel to that of the top. With such a construction in which the top of the frame is inclined upwardly away from the

operator, the presentation of all kinds of work is greatly facilitated; and a tubular knife having a considerable diameter, for example six inches or more, may be used while still maintaining the distance from the top of the front wall to the adjacent exposed edge of the knife very small.

The feed roll carrier (Fig. 3) is in the form of a yoke 157, the ends of the arms of which are rotatably mounted on a rod 159 having an enlarged portion at its outer end which is threaded through a bore in the swinging part 121 of the frame and is held in adjusted position by a lock nut 161. The yoke is held from longitudinal movement on the rod by a collar 163 and a shoulder on the rod 159, said rod being of reduced diameter where it passes through the ends of the arms of the yoke. The yoke 157 (Fig. 6) has a downwardly extending arm 167 provided with a small pin 169, the head of which is in contact at all times with a spring-pressed plunger 171 slidably mounted in a bore in a hollow screw 173, which is threaded through a boss on one wall of the swinging part 121 of the frame. By turning the screw 173, the tension of the spring 175 may be varied. Driven into the opposite side of the downwardly extending arm 167 of the yoke 157 below the pin 169 is a second pin 177, which is held by the action of the compression spring 175 against a stop in the form of an eccentric pin 179 on the inner end of a small angularly adjustable shaft 181, the outer end of which projects through the rear wall of the swinging part 121 of the frame (Fig. 3) and has a pin 183 extending through it to serve as a handle by which it may be turned. A set screw 185, threaded through a wall of the swinging part 121 of the frame into contact with the adjustable shaft 181, holds said shaft in adjusted angular position. With the construction thus far described, the compression spring 175 normally holds the roll carrying yoke 157 and the feed roll 129 in the position shown, but permits the yoke and roll to yield about the axis of the rod 159, thus providing for bodily yielding movement of the feed roll.

The feed roll is also mounted for angular or tipping movement about an inclined axis, which passes through a point *z* (Fig. 4) at the outer upper corner of the roll. The roll is rotatably mounted upon the stem of a screw 187, the head of which is seated in a socket in one end of the roll, the other end of the screw being threaded into a split portion of a block 189 and held firmly by a pinch bolt 191, a washer 192 being interposed between the end of the roll and the block. The block 189 (Figs. 2 and 6) has integral with it a cylindrical stem 193 rotatably mounted in a bore in a boss on one arm of the yoke 157. The bore is inclined upwardly from left to right, as viewed in Fig. 6, and its axis passes through the point *z* (Fig. 4). A small screw 194 (Fig. 6), threaded into one end of the stem 193 and carrying a washer 196 holds the stem 193 in the inclined bore. The roll 129 is normally held in the angular position shown, with reference to the axis which passes through the point *z*, by a torsion spring 195 which is wound about a small rod 197, one end of the spring being fast to a collar 198 which is pinned to the rod. The other end of the spring extends beneath and exerts upward pressure upon the underside of a small screw 201 threaded into a bracket 389 which is fastened to the block 189 by screws 190. The torsion spring at all times urges the roll upwardly about the axis of the stem 193 as far as a stop 207 carried by the yoke 157 will permit. The rod 197 (Fig.

3), which carries the torsion spring 195 and has a hexagon head, passes through a split bearing in the yoke 157 and is held in adjusted angular position by a pinch bolt 209. The feed roll 129 (Figs. 4 and 6) is slotted circumferentially, and a comb 211 has teeth extending into the slots, said comb being fastened by screws 213 to the block 189.

Referring now to Fig. 2, it has been explained that the feed roll is driven from a horizontal shaft 137, which is mounted in bearings in the main part 125 of the frame. This shaft is urged at all times to move to the left by a compression spring 217 located between a part of the main frame and a collar 219, which is fast to the shaft 137, the extent of such movement being limited by contact with one of the bearings for the shaft of the hub of an internal gear 215, which is fast to one end of the shaft. Meshing with this internal gear is a pinion 221 fast at one end of a short shaft 223 having fast to its outer end two pulleys 225, 227, which are formed on a common hub. A belt 229 may be caused to run over the pulleys 43 and 225, as shown, or over the pulleys 45 and 227, according to what speed of rotation is to be imparted to the shaft 223. In order to provide means for tightening the belt 229, the short shaft 223, which carries the pinion 221, is mounted out of line with the shaft 137 in a bearing having integral with it a circular flange 231, which is rotatable in a circular aperture in a wall of the frame, said aperture and said circular flange being coaxial with the shaft 137. Integral with the circular flange 231 is a flange 233 of larger diameter, the rim of which is clamped against the frame of the machine by cap screws 235, the stems of which are threaded into the frame and the heads of which overlap the flange 233. After the cap screws have been loosened, the bearing, in which the short shaft 223 is mounted, may be turned to vary the distance of the pulleys 225, 227 from the pulleys 43, 45, while maintaining the pinion 221 in mesh with the internal gear 215. In order to facilitate turning this bearing, its hub is provided with rectangular recesses 237 to receive a screw-driver or other tool.

The work is held against the feed roll 129 by a presser which may be in the form of a driven presser roll, as herein shown, or in the form of a presser foot or an idle presser roll, said presser being carried by the overhanging arm of a hollow head 239. The present machine is provided with two of these heads, one carrying a driven presser roll and the other carrying either a presser foot or an idle presser roll, said heads being readily removable and replaceable. The illustrated machine is shown with the head which carries the driven presser roll. The hollow head comprises a base (Fig. 3), which is fastened by cap screws 241 to the top of the main part of the frame over an opening in said top. At the outer end of the overhanging arm of the head a stem 243, rectangular in cross-section, is mounted for sliding movement in a path which is perpendicular to the inclined plane of the top of the frame, said stem being urged upwardly by a compression spring 245 as far as an adjustable screw 247 will permit. The stem has at its upper end a cylindrical transverse portion (not shown) about which it may be swung to some extent toward and from the observer. An adjusting screw 249 engages one face of the stem, and a similar screw (not shown) engages the other face, the two screws determining the angular position of the

stem. The mounting of the stem 243 for sliding vertical adjustment and for swinging adjustment toward and from the observer, as viewed in Fig. 3, form no part of the present invention and 5 may be the same as that disclosed in United States Letters Patent No. 1,469,849, granted October 9, 1923, upon an application filed in my name.

At the lower end of the stem 243 is a transversely extending slotted head 251, in which is received the upper part of a presser roll carrier 253, which is pivoted to the transverse head 251 about the stem of a pin 255. A leaf spring 257, one end of which is fastened to the head 251 and 10 the other end of which bears upon a tail on the presser roll carrier 253, holds said carrier in an angular position determined by an adjusting screw 259, which is threaded through the head and contacts with the roll carrier, a coiled spring 261 preventing the screw 259 from accidental turning. The presser roll 263 is fast to a small spindle 265, which has at its rear end an enlarged portion. Between this enlarged portion and the larger end of the roll is a bushing 267, a portion 15 of reduced diameter of which is clamped by a pinch screw 270 in a pinch bearing formed in a downwardly projecting portion of the carrier 253. The outer end of the small shaft 265 is rotatably mounted in a bearing in a second downwardly projecting portion of the carrier. The presser roll is rotated through a small shaft 271, which is connected at one end to the enlarged end of the shaft 265 by a universal joint and at the other end by a second universal joint to one end 20 of a short shaft 273 rotatably mounted in bearings in the hollow head 239. This shaft carries a spiral gear 275, which meshes with a second spiral gear 277 on a horizontal shaft 279 mounted in the head. Also on the horizontal shaft behind the gear 277, as viewed in Fig. 3, is a spiral gear 281 (Fig. 1^a) which meshes with a spiral gear 283 on an inclined shaft 285, said shaft having an oiler 287 at its upper end. The shaft 285 (Fig. 1^a) is rotatable in a bushing 288, the reduced upper portion of which is driven into a bore in the lower portion of the hollow head 239, said shaft having at its lower end a spiral gear 289. The lower portion of the shaft 285 and of the bushing 288 extend down through the opening in the top of the main frame, and the spiral gear 289 meshes with a spiral gear 291 (Fig. 2) on the shaft 137, through which the feed roll is driven. With this construction, the head with the driven presser roll carried by it may readily 25 be removed and replaced, either by another head having a differently shaped driven presser roll, or by a head having a presser foot or an idle presser roll.

There is a space (Fig. 6) between the rear wall of the tubular knife and the edge of the top of the frame so as to provide for longitudinal adjustment of the knife; and in order to prevent chips and other foreign matter from falling into this space, there is provided (see also Fig. 5) a cover plate 293, the forward end of which bridges this space. This plate is flat on its under side and is provided with a rib which enters a longitudinal guideway formed in the top of the frame so as to permit the plate to be adjusted 30. The plate has fastened to it by a screw 295 the upper end of a pin 297, the lower end of which extends loosely into a socket in the cap 31, said cap, it will be recalled, being fast to the cylindrical carrier 21 of the knife shaft. Consequently, when this carrier is adjusted to adjust the knife,

the cover plate 293 is also adjusted, its position with respect to the knife remaining unchanged with the result that the space between the rear wall of the knife and the adjacent edge of the top of the frame is always covered by the plate. This construction also permits the cover plate to be removed at any time merely by lifting it up.

Although the invention has been set forth as embodied in a particular machine, it should be understood that the invention is not limited in the scope of its application to the particular machine which has been shown and described.

Having described my invention, what I claim as new and desire to secure by Letters Patent of the United States is:

1. A skiving machine having in combination a rotary tubular knife, a feed roll located partly within the knife, a presser which cooperates with the feed roll, said knife having an outside bevel along its cutting edge and being adjustable longitudinally, and a rotary grinder having an operative face which is all in one plane, said grinder being angularly movable into and out of operative position about an axis which is parallel to the axis of rotation of the knife.

2. A skiving machine having in combination a rotary tubular knife, a feed roll located partly within the knife, a presser which cooperates with the feed roll, said knife having an outside bevel along its edge and being longitudinally adjustable, a rotary shaft parallel to the axis of rotation of the tubular knife, a casing rotatable about the axis of said shaft, a short shaft mounted for rotation in the casing, said shaft being at an oblique angle to the first-named shaft, gears connecting the two shafts, a grinder carrier by the short shaft, and means for swinging the grinder into and out of contact with the bevel along the edge of the tubular knife.

3. A skiving machine having in combination a rotary tubular knife, a feed roll located partly within the knife, a presser which cooperates with said feed roll, said knife having an outside bevel along its cutting edge and being adjustable longitudinally, a rotary grinder angularly movable into and out of operative position about an axis which is parallel to the axis of rotation of the knife, and means for so moving the grinder, said means including a spring constantly urging the grinder to move in one direction and an adjusting rod rotation of which moves the grinder in the opposite direction, said rod carrying a ball which is held by the force of the spring against a spherical socket in the frame of the machine.

4. A skiving machine having in combination a rotary tubular knife, a work support above the surface of which the knife projects, a feed roll located partly within the knife, a presser which cooperates with the feed roll, a shaft from which the feed roll is driven, a gear fast to said shaft, a driven pulley rotatable about an axis which is eccentric to the axis of said shaft, a belt for driving said pulley, and a pinion rigid with the pulley and meshing with the gear, said pulley and pinion being adjustable in a circular path about the axis of said shaft.

5. A skiving machine having in combination a rotary tubular knife, a feed roll located partly within the knife, a presser cooperating with the feed roll, a block by which the roll is carried, said block having a stem the axis of which passes substantially through the upper outer corner of the roll, a yoke in which said stem is mounted for rotation, a stop mounted on the yoke for limiting the extent of the rotation of the block, a torsion

spring one end of which engages the underside of the block and normally holds it against the stop, a rod about which a portion of the spring is wound and to which one end is fast, a split bearing formed in the yoke through which the rod passes, and a pinch screw for clamping the rod in adjusted angular position.

6. A skiving machine having in combination a rotary tubular knife, a feed roll located partly within the knife, a presser cooperating with the feed roll, a block by which the feed roll is carried, said block having a stem the axis of which passes through the upper outer corner of the feed roll, a rotatable yoke in which said stem is rotatably mounted, said yoke having a stop to limit the extent of rotation of the block, a torsion spring carried by the yoke and normally holding the block against the stop, a compression spring for rotating the yoke, and a stop for limiting the extent of such rotation.

7. A skiving machine having in combination a hollow frame having an opening in its top, a rotary tubular knife, a feed roll located partly within the knife, a driving member located in the frame beneath said opening, a head detachably fastened to said top and having a portion extending into said opening, a presser roll carried by the head, and mechanism carried by the detachable head for connecting the presser roll with the driving member.

8. A skiving machine having in combination a hollow frame having an opening in its top, a rotary tubular knife, a feed roll located partly within the knife, a driving member located in the frame beneath said opening, a hollow head detachably fastened to said top and having a portion extending into said opening, a presser roll carried by the head, and mechanism including gearing located within said hollow head for connecting the presser roll with the driving members.

9. A skiving machine having in combination a frame having an opening in its top, a rotary tubular knife, a feed roll located partly within the knife, a head detachably mounted upon the top of the frame and having an extension which projects down through an opening in the top, a presser roll carried by the head, and mechanism including a gear carried by the downwardly projecting portion of the detachable head for rotating the presser roll.

10. A skiving machine having in combination a frame having an opening in its top, a rotary tubular knife, a feed roll located partly within the knife, a head detachably mounted upon the top of the frame and having an extension which projects down through an opening in the top, a presser roll carried by the head, a gear located in the frame beneath the opening in the top thereof, and mechanism carried by the detachable head and including a gear supported by the downwardly projecting portion of the head and adapted to mesh with said first-named gear for rotating the feed roll.

11. A skiving machine having in combination a tubular knife, a shaft by which the knife is carried, a feed roll located partly within the knife, a presser cooperating with the feed roll, a chip deflector located within the knife and having a stem threaded into a socket in the end of the knife shaft whereby the chip deflector may be adjusted longitudinally of the knife, and a screw threaded into a hollow in said stem and engaging the bottom of the socket in the end of the knife shaft.

12. A skiving machine having in combination a hollow frame a portion of which serves as a work support, said frame being higher at the back than at the front so that the top is inclined from rear to front, a rod parallel to the inclined top of the frame, said rod being threaded through the back wall of the frame so as to be adjustable lengthwise, a feed roll carrier pivoted on the rod for yielding movement in a path at right angles to the rod, a feed roll pivoted to the carrier for yielding movement in a path parallel to the rod, a tubular knife partly enclosing the feed roll, and a rotary shaft on which the knife is mounted.

13. A skiving machine having in combination a hollow frame a portion of the top of which serves as a work support, said frame being higher at the back than at the front so that the top is inclined from rear to front and the space in the rear part of the frame is larger than that in the front part, a rod parallel to the inclined top of the frame, said rod being threaded through the back wall of the frame so as to be adjustable lengthwise, a feed roll carrier in the form of a yoke pivoted on the rod for yielding

5 movement in a path at right angles to the rod, a feed roll pivoted to the yoke for yielding movement in a path parallel to the rod, a tubular knife partly enclosing the feed roll, a rotary shaft on which the knife is mounted, means located in the rear part of the frame for adjusting the yoke about the rod, a shaft located in the rear part of the frame below the level of the knife shaft, and a grinder adjustable about the axis 10 of the shaft.

14. A skiving machine having in combination a tubular knife, a rotary shaft on one end of which the knife is mounted, ball bearings in which said shaft is rotatable, a cylindrical carrier for said ball bearings, a spacing sleeve surrounding the shaft and in contact at one end with one ball bearing and at the other end with the other ball bearing, a member threaded upon the shaft and adapted to exert force through one ball bearing and the sleeve to hold the other ball bearing against a shoulder on the shaft, and means for adjusting the carrier longitudinally and with it the shaft and the ball bearings.

EUGENE J. RAY.

CERTIFICATE OF CORRECTION.

Patent No. 2,250,497.

July 29, 1941.

EUGENE J. RAY.

It is hereby certified that error appears in the printed specification of the above numbered patent requiring correction as follows: Page 5, first column, line 36, claim 2, for the word "carrier" read --carried--; and that the said Letters Patent should be read with this correction therein that the same may conform to the record of the case in the Patent Office.

Signed and sealed this 23rd day of September, A. D. 1941.

(Seal)

Henry Van Arsdale,
Acting Commissioner of Patents.
